CLAIM

The ornamental design for a dispensing container, as shown and described.

DESCRIPTION

FIG. 1 is a perspective top view of the dispensing container; FIG. 2 is a side elevational view of the front thereof; FIG. 3 is a side elevational view of the back thereof; FIG. 4 is a third side elevational view thereof, the remaining side view is symmetrical therewith; FIG. 5 is a top plan view thereof; FIG. 6 is a bottom plan view thereof; and, FIG. 7 is a further perspective view of the dispensing container, in an open configuration which illustrates further details of the design.

The broken lines in the drawings depict portions of the dispensing container that form no part of the claimed design.

1 Claim, 6 Drawing Sheets
